UNITED STATES PATENT OFFICE.

CHARLES JOHNSON, OF AUBURN, AND CHARLES FRANK, OF SENECA FALLS,
NEW YORK.

MANURE-SPREADER.

1,025,403.

Specification of Letters Patent.

Patented May 7, 1912.

Application filed May 22, 1909. Serial No. 497,773.

To all whom it may concern:

Be it known that we, CHARLES JOHNSON and CHARLES FRANK, citizens of the United States, residing, respectively, at Auburn, in the county of Cayuga, and Seneca Falls, in the county of Seneca, in the State of New York, have invented new and useful Improvements in Manure-Spreaders, of which the following, taken in connection with the accompanying drawings, is a full, clear, and exact description.

This invention relates to the style of manure spreading machine in which a change-speed gearing is employed for driving the longitudinally movable apron which constitutes the bottom of the body of the machine.

The main object of the present invention is to produce a machine which shall be very efficient and reliable in its operation and capable of distributing the fertilizing material over a wide stretch of ground, and a further object is to provide simple and conveniently controlled mechanism for driving the beater and apron.

To that end the invention consists primarily in the novel construction and arrangement of the sectional beater and its driving mechanism, and secondarily in the novel construction and combination of the component parts of the change-speed mechanism for transmitting motion from the beater to the apron, as hereinafter described and set forth in the claims.

Referring to said drawings Figure 1 is a top plan of a manure-spreader embodying our improvements; Fig. 2 is an enlarged detail rear view of the sectional beater; Fig. 3 is a longitudinal section of said beater; Figs. 4 and 5 are enlarged detail inner face views of the disks which constitute the coupling of the beater-sections.

Like numerals of reference indicate like parts in the several views of the drawings.

—1— denotes the box or body of the vehicle which is mounted upon the front axle —2— and rear axle —3— in any suitable or well known manner, and —4— denote the rear or traction-wheels journaled on the axle —3— in the usual manner.

—5— represents the usual longitudinally movable apron which constitutes the bottom of the vehicle-body and may be of any suitable form.

At the rear end of the body is arranged our improved beater composed of two sec-

tions —9— secured respectively to separate horizontal shafts —10— which are set out of parallelism in relation to the apron shafts, and are arranged rearwardly convergent at a line extending centrally and longitudinally through the body. Each of the shafts —10— is journaled at its outer end in a suitable bearing —11— provided on the inner side of an upright bracket —12— fastened to the sill of the body, the inner ends of which shafts are journaled in bearings —13— provided on bracket-arms —14— formed on a standard —15— bolted to a cross-bar —16— which may be bolted or otherwise fastened at its ends to the inner sides of the sills as more clearly illustrated in Fig. 3 of the drawings. Each of said beater-sections comprises a series of parallel bars —17— provided with the usual radially disposed teeth —17— and bolted or otherwise secured at their ends to flanges —18— formed on circular heads —19— which are provided with hubs —20— fastened to the shaft by means of pins —21— and abutting against the shaft bearings —11—. The shafts —10— of the beater-sections are connected together by means of a loose-coupling owing to their convergent relation. This coupling consists preferably of two disks —22— which are keyed to the adjacent ends of the respective shafts, the disk —22— being provided with a series of radial slots 24— through which pass clutch arms —25— projecting from the adjacent face of the disk —23—. By this slot- and pin-connection between the two beater-sections, the section —9— drives the other section —9—, the former being driven from the traction-wheel —4— at the corresponding side of the vehicle by mechanism which will now be described.

On the rear axle —3— is loosely mounted a large sprocket wheel —26— which is connected by a chain —27— to a smaller sprocket-wheel —28— journaled on an arbor —29— secured to the outer side of the bracket —12—. The sprocket-wheel —26— is adapted to be shifted longitudinally on the axle and is provided on its outer side with a clutch-face —30— designed to be thrown into and out of engagement with a corresponding shaped clutch-member —31— having its hub fastened to the axle.

To shift the sprocket-wheel —26— longitudinally on the axle —3— to throw the clutch-face —30— into and out of engagement with the co-operating clutch-member 5 —31—, we prefer to employ a lever —39— which extends along the outer side of the body and is formed at its rear end with a bifurcation —40— which engages a circumferential groove —41— provided in the hub 10 of the sprocket-wheel, the forward end of which lever is connected by means of a pivot pin —42— to an ear —43— formed on a plate —44— bolted or otherwise secured to the body as more clearly shown in Fig. 1 of 15 the drawings. The forward end of said lever may be provided with a longitudinal slot not shown for receiving the pivot-pin —42— to allow the lever to move lengthwise slightly during the operation of shifting the 20 sprocket-wheel in order to guard against binding at the connection between the lever and sprocket-wheel. Any suitable manually-operated means may be employed for actuating the said lever —39—, however, we 25 prefer the device shown which comprises a pair of toggle arms —46— which are joined by a suitable coupling —47—, one arm being pivotally connected to the lever as indicated at —48— and the other arm 30 pivotally connected to the vehicle body in any suitable and convenient manner. The said coupling —47— is provided with a socket-portion —50— in which is suitably secured the rear end of a rod —51— extending 35 to the forward end of the body and pivotally connected thereto to a hand-lever —52— by means of any well known coupling, said hand-lever being connected to the body in such position as to be conveniently 40 operated by the person seated upon the vehicle. The rear sprocket-wheel —28— drives a gear —54— journaled on the arbor —29—. The teeth of said gear are set slightly at an angle to the axis of the arbor 45 so as to mesh with a pinion —55— which is secured to the shaft —10— of the beater-section —9— in any well known manner.

By the described construction and arrangement of the parts of the chain and 50 sprocket-mechanism and gearing it will be seen that when the two parts of the clutch are in engagement the forward travel of the left-hand traction-wheel —4— will impart rearward rotation to the beater-section 55 —9—, which latter transmits like rotation to the companion section —9— through the medium of the coupling members hereinbefore referred to. The apron —5— may be driven by any suitable mechanism but is 60 preferably driven from the outer end of the

right-hand beater section by suitable transmitting mechanism —59—, Fig. 1.

The series of teeth —17— of the beater-sections are disposed parallel and the teeth of each bar 65 are preferably arranged in a straight line and gradually shortened toward the outer end of the section as clearly illustrated in Figs. 13 and 14. By thus graduating the series of teeth and arranging the beater-sections convergently as described and shown, the spreading of the manure is very 70 effectual and other advantages are derived.

What we claim as our invention is:—

1. In a manure spreader, a box having a longitudinally movable bottom, a rotary beater composed of rearwardly inclined sections having their axes converging at a point approximately in the plane of the longitudinal center of the box, each section 80 having a series of bars arranged about and parallel with its axis, each bar having a series of teeth projecting at gradually increasing distances from its outer face from one end toward the other end. 85

2. In a manure spreader, a box having a longitudinally movable bottom, a rotary beater composed of sections arranged end to end with their axes converging rearwardly to a point in proximity to the plane of the longitudinal center of the box, each beater section having a series of bars arranged around its axis with their outer faces parallel with said axis, each bar having a series 90 of teeth projecting gradually increasing distances therefrom from its outer end toward its inner end, each beater section having a rotary shaft and a universal joint connection between the inner ends of the shafts. 95

3. In a manure spreader, a box having a rearwardly movable bottom and actuating means therefor, a rotary beater composed of sections arranged end to end and having separate rotary shafts disposed in rearwardly converging angles and having their inner ends coupled together by a universal joint, bearings for the outer ends of the shafts, additional bearings for the inner ends of the shafts, each beater section having a series of bars arranged about and parallel 105 with their respective shafts, and teeth on the bars projecting gradually increasing distances therefrom from their outer ends toward their inner ends. 110

CHARLES JOHNSON.
CHARLES FRANK.
